VACUUM CLEANER ATTACHMENT

Oscar A. Ross, New York, N. Y.

Application May 14, 1936, Serial No. 79,802

7 Claims. (Cl. 15—155)

This invention relates to vacuum cleaners and more particularly to attachments employed in connection therewith for collecting foreign matter by suction and particularly that class of attachment employed for cleaning rugs, draperies, etc.

Vacuum cleaner attachments now employed for the cleaning of rugs, draperies, etc. are made of metal or other hard substance and when employed for cleaning purposes great care must be exercised to prevent the accidental striking of furniture, baseboards, walls or other highly finished surfaces with said attachments otherwise scratches or other undesirable marks or blemishes will occur. This undue care places an undue strain on the person doing the cleaning and careless persons will cause an undue expense due to the necessity of re-finishing said furniture and other highly finished surfaces.

20 This invention comprehends the furnishing of a vacuum cleaner attachment for cleaning rugs, draperies, etc. which will prevent the marring or blemishing of highly finished surfaces on furniture or other surfaces should said attachments accidentally come in contact therewith, this advantage being accomplished by embedding a rigid frame or support in a resilient plastic housing whereby the exterior or exposed surfaces of said attachment are pliable and therefore yield when moved into contact with said highly finished surfaces.

The invention further comprehends the furnishing of an attachment having a resilient exterior surface, however also having the suction nozzle portion formed of hard material for the purpose of reducing friction between said nozzle and the surface being cleaned.

The invention further comprehends novel and peculiar modes of quickly and detachably coupling said attachments to the rigid extension or pipes to which said attachments are generally coupled and further comprehends a novel form of rigid extension or pipe having a resilient exterior surface whereby accidental striking thereof against highly finished surfaces of furniture or other furnishings or fixtures will prevent marring or blemishing the same.

Other novel features and advantages will be apparent as the description of the invention progresses and the novel and peculiar structure and features thereof will be pointed out herein, and wherein:—

Figure 1 is a rear elevational view of one embodiment of the invention taken on line 1—1 of Fig. 2, and Fig. 2 is a sectional view of the same

taken on line 2—2 of Fig. 1, and Fig. 3 is a plan view of the same taken on line 3—3 of Fig. 1, and Fig. 4 is a rear elevational view of a modified form of attachment wherein a modified form of frame or rigid support is shown embedded in the resilient housing, and Fig. 5 is a side elevational view of the same taken on line 5—5 of Fig. 4, and Fig. 6 is a detailed sectional view showing how the resilient material is interlocked to the fabricated metal frame, and Fig. 7 is a 10 part sectional view of a modified form of attachment outlet, and Fig. 8 is a sectional view of still another modified outlet taken on line 8—8 of Fig. 9, and Fig. 9 is a sectional view of the same taken on line 9—9 of Fig. 8, and Fig. 15 15 is a side elevational view of an assembly including an attachment and extension tube therefor, and Fig. 11 is a plan view of a modified nozzle frame.

Referring to Figs. 1, 2, 3 and 6 attachment 1, 20 suitable for the cleaning of rugs, draperies, etc. comprises a frame or rigid support having air and dust outlet portion 2 formed by the junction of semi-tubular stampings 3 and 4 welded at 5, said stamping having extensions 6 and 7 25 secured to nozzle housing reinforcing plates or stampings 8 and 9 in any suitable manner, as for example by spot welds 10. The dust and air outlet portion 2 is arranged to receive a conventional extension tube, or may receive the tube 30 31 shown in Fig. 10. Stampings or plate members 8 and 9, of similar form include clip or hinge portions 11 bent over reinforcing bail or slot shaped frame wire 12 formed from a straight length of wire having exposed portions 13 between said hinge portions. Said frame and hinge portions form the suction inlet 15 of said attachment, the spaces 16 between said hinged portions forming bleeder inlets to prevent said attachment from becoming locked to the surface 40 being cleaned.

The outlet members 3 and 4, nozzle plates 8 and 9 and slot shaped frame 12 form a rigid fabricated frame-like structure or skeleton support over which a resilient cover 17 is molded 45 and interlocked against removal, said cover may be molded of soft vulcanized rubber, or other plastic material and comprises a cylindrical outlet portion 18, the upper or open end of which surrounds the upper end portion 19 of members 50 3 and 4 providing an annulus having a coupling face 20 arranged to engage the tubular extension 51 (Fig. 10) to which said attachment 1 is coupled for cleaning purposes, in this manner providing a resilient coupling engagement between 55

- said attachment and extension. Molded cover or housing 17 further comprises suction nozzle portion 21 having side-walls 22 interlocked to plates 8 and 9 in openings 23, said side-walls 5 being connected by an arched portion 24. Said cover or housing further includes a bead portion 25 interlocked with hinge portions 11 and 12 as shown in Fig. 6, said bead portion acting as a buffer in the event attachment 1 accidentally 10 engages highly finished surfaces of furniture or other fixtures during the use thereof for cleaning purposes.
- Referring to Figs. 4 and 5 showing a modified form of the invention, attachment 30 includes 15 an interior metal housing 31 which may be a unitary structure comprising a casting or stamping having a hard surface suction inlet portion 35 and an outlet portion 32 arranged to receive an extension, as for example, extension 52 of 20 Fig. 10. Suction inlet portion 35 includes a hard surface rubbing face or nozzle portion 36 arranged to engage the surface to be cleaned. Attachment 30 further includes outer housing or cover 36 formed of resilient material, said housing 25 being preferably of rubber or other resilient material, said housing having a cylindrical portion 37 surrounding the outlet portion 32, and a protecting or housing portion 38 surrounding the suction inlet portion 35. Said protecting or 30 housing portion 38 includes bead or buffer portion 39 extending beyond the outer edge of flange portion 34 thereby acting as a resilient buffer in event said attachment engages highly finished surfaces or furniture, or other fixtures 35 while attachment 30 is in use. Buffer portion 39 includes a reinforcing wire or member 40, preferably molded therein for allocating resilient housing 30 with respect to the metal housing 31. Resilient housing 36 may be cemented 40 to metal housing 31, or may be frictionally secured thereto by interlocking the bead portion 39 with the metal housing 31 and suitable rivets 41 may be employed for additionally securing said housing together.
- 45 Referring to Fig. 7 showing a modified form of air and dust outlet portion 50 for use on vacuum cleaner attachments shown in Figs. 1 to 5 inclusive, said outlet comprises metal sleeve portion 52 of enlarged form, also resilient cylindrical portion 53 formed of resilient material preferably molded onto the sleeve portion 52 and interlocked therewith said resilient portion 53 extending downwardly within sleeve portion 52 a sufficient distance to form a female coupling 55 portion for receiving the male coupling portion of tube 51. Sleeve portion 52 is formed with apertures 54 through which the molded resilient material extends for further locking resilient portion 53 onto sleeve portion 52, the resilient 60 material within said aperture acting to lock the outer portion 55 and inner portion 56 of resilient member 53 together and thereby prevent circular movement thereof as extension 51 is twisted into coupling portion or outlet 50 for the 65 coupling thereto. Flange 58 formed on sleeve portion 52 also acts to prevent axial movement of cylindrical portion 53, said flange portion being interlocked in bead portion 57 of said cylindrical portion 53.
- 70 Referring to Figs. 8 and 9 showing still another modified form of air and dust outlet portion 60 for said vacuum cleaner attachment, said outlet is similar to the outlet described in connection with Figs. 1, 2 and 3 however sleeve 61 75 is formed spacedly from the coupling end of the

extension tube which it is to receive and is provided with inwardly extending, preferably stamped bosses 62 which engage the coupling end of said extension tube for positively engaging same as the attachment and tube are coupled together. Resilient molded covering 63 is locked against rotation by being molded into depressions or dents 64 produced in forming bosses 62, and is also locked against axial movement by enlarged annular portion 65 of metal sleeve 61.

10 Referring to Fig. 10 metal extension tube 51 is assumed to have oppositely facing tapered male ends for frictionally receiving the attachments as 1 or 30. Extending over the exterior surface of said tube is a resilient covering 51a, said 15 covering extending spacedly between the ends thereof a sufficient distance whereby the coupling portions of said tube are free to be coupled. Said resilient covering is preferably formed with a bead at each end thereof for the 20 purpose of artistically mating with the bead, as for example 57 of the outlet portion 50, said bears being preferably of the same diameter. Said resilient covering 51a is preferably cemented to extension tube 51, however may be frictionally secured thereto, or may be secured by suitable interlocking devices, as for example rivets.

25 Referring to Fig. 11, showing a modified form of fabricated nozzle frame 70, said frame 30 comprises metal loop or slot shaped member 72, preferably of wire to which are attached one end of connecting members 72-72 and 73-73 welded or otherwise secured thereto, the other end of said members being preferably welded to suction inlet collar or annular member 71.

35 Whereas the air and dirt outlet portions 3 and 4 are shown as being butt welded together, one of said members may have flange portions overlapping said other member for spot welding 40 or otherwise securing said parts together, or said portions 3 and 4 may be made as a single stamping.

45 From the foregoing description it will be seen that the applicant has furnished novel and peculiar forms of attachment and outlet and inlet portions thereof and novel and peculiar extension tubes which are novelly coupled to said attachment for forming a vacuum cleaner assembly which may be employed for the cleaning of rugs, draperies or other surfaces without the danger of marring or blemishing highly finished surfaces of furniture or other structure should said assembly accidentally engage said highly finished surfaces while said assembly is 55 being employed for the cleaning of said rugs, draperies, etc.

50 Applicant's novel structure not only avoids marring or blemishing as described thereby saving the expense of repairing said marring or 60 blemishes but also has the advantage of relieving an operator of undue strain in attempting to avoid said highly finished surfaces during the operation of vacuum cleaning.

65 It is to be understood that extension attachment 51 may have both male ends or male and female ends, the female ends being formed in the peculiar manner disclosed hereinbefore.

70 The vacuum cleaner attachments above illustrated and described should be construed as typical and not as limiting the invention, the scope of which is defined in the appended claims.

75 What I claim is:

1. In a vacuum cleaner attachment, a rigid support having a suction inlet portion including

- a suction inlet for engaging a surface to be cleaned and an annular suction outlet portion including an inner coupling face for engaging a correlated removable attachment, a housing 5 formed of plastic resilient material in which said support is embedded, and a coupling portion on said resilient housing having a coupling face forming a continuation of said inner coupling face on said outlet portion for also engaging 10 said correlated attachment when inserted into said vacuum cleaner attachment.
2. In a vacuum cleaner attachment, a rigid metal support having a suction inlet nozzle portion including a suction inlet opening for engaging a 15 surface to be cleaned, a suction outlet coupling portion on said support having a suction outlet opening for communication with a correlated removable attachment, said inlet and outlet portions being fixed with respect to one another, 20 and a housing formed of plastic resilient material in which said support is embedded extending between said inlet and outlet openings including a portion extending downwardly into the opening of said suction outlet coupling portion.
3. In a vacuum cleaner attachment, a rigid support having a suction inlet nozzle portion including a suction inlet opening for engaging surfaces to be cleaned, a suction outlet coupling portion on said support having a suction outlet 25 opening for communication with a removable correlated attachment, and a housing formed of plastic resilient material in which said support is embedded extending between said inlet and outlet openings, the portion of said housing adjacent 30 said inlet opening being spaced therefrom whereby said support will engage said surfaces, and the housing portion adjacent said suction outlet opening extending downwardly within said opening for engaging said correlated attachment when inserted into said vacuum cleaner attachment.
4. In a vacuum cleaner attachment, a rigid support comprising a suction outlet coupling portion having a suction outlet opening and a 35 suction inlet nozzle portion including a suction inlet opening, and a resilient housing formed of plastic material in which said support is embedded, said housing having a suction outlet portion surrounding said support coupling portion and extending downwardly within the opening therein and a suction inlet portion terminating spacedly from the suction inlet opening in said support nozzle portion and a female coupling face on the portion of said housing extending downwardly in said suction outlet open- 40
- ing for engaging a male coupling face on a correlated attachment.
5. In a vacuum cleaner attachment, a rigid support comprising an annular coupling structure for attachment with a correlated removable attachment and a slotted nozzle structure rigidly connected together by a flaring skeleton structure, and a resilient housing formed of plastic material in which said support is embedded comprising an annular portion including a suction 10 outlet opening surrounding said coupling structure, a slotted nozzle portion including a suction inlet opening surrounding said nozzle structure and interlocked therewith, and a hollow flaring portion connecting said coupling and nozzle portions for forming a suction tight chamber between said openings. 15
6. In a vacuum cleaner attachment, a rigid metal support comprising a suction inlet nozzle structure having a suction end face surrounding a suction opening for engaging a surface to be cleaned, a suction outlet coupling structure including an outlet opening for receiving a correlated attachment and an intermediate skeleton structure rigidly connecting said nozzle and coupling structures, and a resilient housing formed of plastic material in which said support is embedded comprising an orificed nozzle portion surrounding said nozzle structure, an orificed coupling surrounding said coupling structure and a hollow housing portion connecting said nozzle and coupling portions for forming a suction tight chamber between the orifices of said nozzle and coupling portions, said suction end face extending beyond said orificed nozzle portion of said 30 resilient housing. 35
7. In a vacuum cleaner attachment, a rigid skeleton support comprising a rigid annular coupling member having a suction outlet opening adapted to be removably attached to a correlated attachment, a rigid nozzle member having a slot shaped opening and a plurality of spaced rigid re-enforcing members rigidly connecting said coupling and nozzle members in spaced relation, and a resilient housing formed of plastic material in which said support is embedded comprising an orificed coupling portion surrounding said coupling member, a nozzle portion having a slot shaped orifice surrounding said nozzle member and a hollow housing portion connecting said coupling and nozzle portions and surrounding said re-enforcing members for forming a suction tight chamber between the openings of said support. 40 45 50

OSCAR A. ROSS. 55
